(57) **CLAIM**

The ornamental design for a flashlight, as shown.

DESCRIPTION

The claimed flashlight is used to illuminate areas of undesirably low light and could be held in hand or mounted on another object, such as a weapon.

FIG. 1 is a front perspective view of a flashlight showing my new design;

FIG. 2 is a front elevational view thereof;

FIG. 3 is a left side elevational view thereof;

FIG. 4 is a rear plan view thereof;

FIG. 5 is a right side elevational view thereof;

FIG. 6 is a top plan view thereof; and,

FIG. 7 is a bottom plan view thereof.

The broken line showing is for illustrative purposes only and forms no part of the claimed design.
